UNITED STATES PATENT OFFICE.

JAMES H. DYETT, OF BROOKLYN, NEW YORK.

LUGGAGE GUARD.

Application filed June 2, 1923. Serial No. 643,068.

This invention relates to improvements in luggage guards, and has particular reference to a guard adapted for attachment to the running board of a vehicle.

5 An object of the invention is to provide an improved guard which is so constructed that the length thereof may be varied in accordance with the size of the running board to which it is attached.

10 Another object is to provide a guard of simple and comparatively inexpensive construction, which is so organized that the same may be readily applied to any type of running board.

15 The above and other objects will appear more clearly from the following detail description, when taken in connection with the accompanying drawings, which illustrate preferred embodiments of the inventive idea.

20 In the drawings—

Figure 1 is a plan view of the luggage guard applied to a running board and shown in one of its adjusted positions;

Figure 2 is an end elevation thereof;

25 Figure 3 is a section substantially on the line 3—3 of Figure 2;

Figure 4 is a section on the line 4—4 of Figure 1;

30 Figure 5 is a view similar to Figure 2, showing the guard in another of its adjusted positions;

Figure 6 is an end elevation of the guard showing the same in its inoperative or folded position; and

35 Figure 7 is a transverse sectional view showing a slightly different form of the invention.

Referring more particularly to the accompanying drawings, the numeral 10 indicates the running board of a vehicle to which the guard is attached. The guard includes the end supports 11 having vertically arranged flanges 12. These end supports may be secured to the upper surface of the

40 running board by any suitable fastening devices, such as the screws 13. A connecting link 14 is associated with each of the end supports 11 and is pivotally connected to the enlarged end of the flange 12 by means

45 of a screw member 15 which extends through said flange. These connecting links are designed for adjustment to various angles with respect to the end supports and for this purpose are provided with projections 16 upon their outer faces which engage in depressions or openings 17 formed in the

enlarged end of the flange 12, said projections and openings being arranged concentrically with respect to the screw member 15 about which the link moves as a pivot. 60 In order that the link 14 may be secured in any one of its various adjusted positions, a wing nut or other suitable fastening device 18 is threaded upon the member 15 and when turned in the proper direction will engage the flange 12 and thus draw the adjacent end of the connecting link outwardly so as to seat the projections 16 in the openings 17, thereby preventing any further turning of the link about its pivot. 70

The guard further comprises a frame including the end members 19 each of which has extending therefrom intermediate its ends the screw member 20 which extends through a suitable opening formed in the 75 other end of the connecting link 14. The last named end of the link 14 is provided upon its inner face with a plurality of projections 21 similar to the projections 16 and engageable in openings 22 formed in the end member 19 intermediate the ends thereof. 80 This end member is designed to rotate about the screw member 20 as a pivot and the latter has mounted thereon a wing nut 23 which, when tightened, will engage the projections 21 in the openings 22 and thus prevent any rotary movement of the member 19 85 after the same has been adjusted to the desired angle.

Each of the end members 19 forms a part 90 of one section of the frame which is adjustable longitudinally with respect to the other section thereof before the guard is attached to the running board in order to vary the effective length of the guard. One of the 95 sections of the frame includes a plurality of longitudinal bars 24 which, in the form of the invention shown in Figures 1 to 6, are of T shaped formation. Adjacent ends of these bars are secured in any preferred manner to one of the end members 19 and extend therefrom in parallel and spaced relation with respect to each other. The other end member 19 of the frame also has extending therefrom the guide bars 25 formed 100 of sheet metal and bent transversely to conform to the contour of the T bars 24, the portions of the bars 25 adjacent the longitudinal edges thereof overlapping, as indicated at 26, so that portions of the T bars 110 are telescoped within the bars 25 and completely surrounded. By thus constructing

the bars 25 the same will afford effective guides for the bars 24, which will permit of the same being adjusted longitudinally of said bars 25 when it is desired to vary the 5 length of the frame. In order that the bars 25 will be maintained in parallel relation and thus prevent any binding of the bars 24 therein, a spacing element 27 is employed, the ends of which are bent, as indicated at 10 28, to engage a portion of the outer bars 25 of the frame adjacent the ends thereof remote from the end member 19 to which the latter bars are attached. The element 27 is also bent or offset, as indicated at 29, 15 to form a groove in which the adjacent outer bar 25 is seated. The element 27 is further bent intermediate its ends to provide a groove 30 for receiving the intermediate bar 25. In the form of the invention shown in 20 Figure 7, the bars 24', which are the equivalent of the bars 24, are of channeled formation and are engaged in the guide bars 25', which are bent to conform to the contour of the bars 24. The longitudinal edges 25 of the bars 25' are bent over the flanges forming the bars 24' to provide grooves in which the latter bars are slidable.

From the foregoing description, it will be apparent that the present invention provides 30 a luggage guard which, previous to its attachment to a vehicle, may be adjusted to any suitable length, after which the end supports 11 may be secured to the running board 10. By reason of the pivotal connections 15 and 35 20 the guard, including the frame, may be swung to numerous angular positions with respect to the running board and may also be folded over on top of said board, as

shown in Figure 6. Then by tightening the various wing nuts 18 and 23, the frame may 40 be secured in any of its adjusted positions.

What is claimed is:

1. An automobile luggage carrier comprising supporting members adapted for securing to a running board, a link pivotally connected to the outer end of each supporting member, a frame pivotally connected intermediate its longitudinal edges to the outer ends of said links, and means for retaining the frame in its desired adjusted 45 position.

2. An automobile luggage carrier comprising supporting members adapted for securing to a running board, a link pivotally connected to the outer end of each supporting member, a frame pivotally connected intermediate its longitudinal edges to the outer ends of said links, and binding members adjacent the pivotal connections of the links to the supporting members and the frame to 60 the links to hold said parts in their desired adjusted positions.

3. An automobile luggage carrier comprising supporting members adapted for securing to a running board with the 65 outer ends of said supports terminating at the outer edge of the running board, a link pivotally connected to the outer end of each supporting member, and a frame pivotally connected to the outer ends of said links to 70 permit one longitudinal edge of said frame to rest against the outer face of the running board when said frame is adjusted to its extreme outward position.

JAMES H. DYETT.
